CABLE SHEARING PLIERS

Leroy E. Lattin, Granada Hills, Calif., assignor to Universal Products Corporation, a corporation of California

Filed Nov. 9, 1967, Ser. No. 9,344

Term of patent 14 years

U.S. Cl. D8—58

Int. Cl. D8—02

FIG. 1

FIG. 2

FIG. 3

FIG. 4

FIG. 5

FIG. 6

FIGURE 1 is a front elevational view of a cable shearing pliers showing my new design;

FIGURE 2 is a rear elevational view thereof;

FIGURE 3 is a side view thereof looking at the left side of the view of FIGURE 1;

FIGURE 4 is an opposite side view thereof looking at the right side of the view of FIGURE 1;

FIGURE 5 is an end view thereof looking at the head end of the view of FIGURE 1; and

FIGURE 6 is an opposite end view thereof looking at the handle end of the view of FIGURE 1.

I claim:

The ornamental design for cable shearing pliers, substantially as shown.
